UNITED STATES PATENT OFFICE.

CARL C. HINKLEY, OF DETROIT, MICHIGAN, ASSIGNOR TO CHALMERS MOTOR COMPANY, OF DETROIT, MICHIGAN, A CORPORATION OF MICHIGAN.

V-TYPE MULTICYLINDER ENGINE.

1,201,731.

Specification of Letters Patent. Patented Oct. 17, 1916.

Application filed November 11, 1915. Serial No. 60,883.

To all whom it may concern:

Be it known that I, CARL C. HINKLEY, a citizen of the United States of America, residing at Detroit, in the county of Wayne 5 and State of Michigan, have invented certain new and useful Improvements in V-Type Multicylinder Engines, of which the following is a specification, reference being had therein to the accompanying drawings.

10 The invention relates to multi-cylinder engines of the V-type, and it is the primary object of the invention to simplify the construction of inlet manifold and the attachment of the carbureter to the same. To this 15 end the invention comprises the construction as hereinafter set forth.

In the drawings: Figure 1 is a cross section through a motor embodying my improvement; and Fig. 2 is a longitudinal section 20 thereof.

A and B are the twin blocks of engine cylinders forming a V-type motor.

C is a crank case on which said blocks are mounted and provided with bearings D for 25 the crank shaft.

It is usual to arrange the carbureter between the blocks and connect the same with twin inlet manifolds therefor. This renders the carbureter less accessible than 30 where arranged at the side of the engine and also complicates the operations of assembly. With my improved construction the carbureter is arranged at one side of the engine and is connected with the cylinders in the 35 twin blocks by an inlet passage through the crank case.

As shown, the crank case C is provided with a partition or web E for centrally supporting the central bearing D thereof, and 40 in this partition is formed an inlet passage F extending from one side to the center and then upward, being bifurcated at G and G' to connect with passages H and H' formed in the blocks A and B. The plane of these 45 passages is preferably at the longitudinal center of the blocks, and at their upper ends the passages H and H' connect with oppositely-extending passages I and I' which connect to the several cylinders in each block 50 by individual passages J controlled by the

valves K. The water-jacket L of each block is also preferably connected with passages L' formed in the crank case partition or web E for connection with the pump and circulating system.

With the construction as described the carbureter M may be mounted directly on the side of the crank case where it is easily accessible, and as the passages F H H' I I' and J are formed by coring the crank case 60 and cylinder blocks a simple and inexpensive construction is obtained.

55 What I claim as my invention is:—

1. In a V-type motor, a crank case formed with a web or partition for supporting the 65 crank shaft bearing, said web or partition having an inlet conduit therein, and twin cylinder blocks secured to said crank case having branch admission conduits registering with said admission conduit in the crank 70 case.

2. In a V-type motor, a crank case having a transversely extending partition with an admission conduit extending from one side of said crank case to the center thereof 75 terminating in an upwardly-extending bifurcation, and twin cylinder blocks having branch admission conduits registering with the furcations of the conduit in said crank case.

3. In a V-type motor, the combination 80 with a crank case having a central partition provided with an admission conduit extending from one side of the case to the center with an upward bifurcation, twin cylinder 85 blocks mounted on said crank case and each having a plurality of cylinders arranged upon opposite sides of said central partition, each of said blocks having an upwardly-extending admission conduit registering 90 with a furcation of the conduit in said case and also having oppositely-extending conduits leading to the several cylinders.

4. In a V-type motor, a crank case and 95 separate twin cylinder blocks, each of said blocks having an inlet conduit formed therein extending longitudinally thereof, with a downwardly-extending portion at the center, and said crank case having an admission conduit extending from one side of the 100

case inward and branched for registration with the conduits in said blocks.

5. In a motor, a crank case formed with a web or partition having an inlet conduit and a passage for the cooling medium therein and a cylinder block secured to said crank case having an admission conduit connecting with said inlet conduit and a surround-

ing jacket connecting with said passage for the cooling medium.

In testimony whereof I affix my signature in presence of two witnesses.

CARL C. HINKLEY.

Witnesses:

ALWIN A. GLORTZNER,
CHARLES LEPEDOMOR.
